UNITED STATES PATENT OFFICE

WILHELM MÜLLER AND JOSEF MARTIN MICHEL, OF BITTERFIELD, GERMANY, AS
SIGNORS TO I. G. FARBEININDUSTRIE AKTIENGESELLSCHAFT, OF FRANKFORT-ON-
THE-MAIN, GERMANY, A CORPORATION OF GERMANY

PROCESS FOR THE PRODUCTION OF CHEMICALLY PURE PHOSPHORIC ACID

No Drawing. Application filed September 19, 1929, Serial No. 393,837, and in Germany September 25, 1928.

This invention relates to the production of chemically pure phosphoric acid.

For purifying acids, it has been proposed to subject them to electrolysis (see Lunge's "Schwefelsäurefabrikation," 2nd volume, pages 1198/1199), but no particulars were given as to the essential details required for a successful refinement of acids.

For purifying technical phosphoric acid which, as a rule, contains arsenic, arsenous acid, phosphorous acid and heavy metals as the most undesired contaminations, various purely chemical methods have been proposed, which, however, generally contemplate the removal of only a single one of these contaminations, in the most cases arsenic.

Now we have found that all the above-mentioned contaminations can be removed from the raw acid in a single operation and in a very simple manner by subjecting the raw acid to an electrolytic refinement, when employing cathodes upon which the metals or metalloids obtained from the contaminations by cathodic reduction are deposited without simultaneously reducing the orthophosphoric acid to lower phosphoric oxides. Chromium, platinum or tantalum may be employed for the cathodes, the best results, however, being obtained with copper or silver cathodes, as these require the lowest decomposition voltage whereby a maximum output of energy is attained. For the anodes only platinum practically comes into consideration. Preferably the cathodic current density is kept below 0.01 amperes per square centimeter, for instance, at 0.005 amperes per square centimeter, whereas the anodic current density may amount to about 0.25 amperes per square centimeter.

By electrolyzing the raw acid, the lower oxides of phosphorus, substantially phosphorous acid are oxidized at the anode to orthophosphoric acid, whereas all metallic contaminations, as well as arsenic and antimony are separated at the cathode. When the electrolysis is completed, the acid is filtered so as to separate particles of the slime precipitated at the cathode which may have passed over into the acid. Moreover our improved process affords the remarkable ad-

vantage that a phosphoric acid of any admissible or occurring concentration, for instance, an acid of 80 to 90%, can be refined immediately after its fabrication. The refining methods hitherto used are limited to acid concentrations of 25% as an upper limit, as the usual precipitation of the heavy metals in the form of sulfides by means of sulfuretted hydrogen is only possible with such low concentrations. In order to oxidize the phosphorous acid when working according to this old method, nitric acid must be added after filtration, and finally the solution is evaporated to the desired concentration in quartz vessels.

Example 1

A raw acid showing a specific gravity of 1.70 at 17.5° C., corresponding to a concentration of 84.5% H_3PO_4 was subjected to our improved process. This raw acid contained the following contaminations:—

	Milligrams per liter
Phosphorous acid	490
Arsenic	25 75
Heavy metals, including iron	240

The raw acid was electrolyzed with anodes of platinum and cathodes of copper, the cathodic current density amounting to 0.004 amperes/cm² and the anodic current density to 0.25 amperes/cm². After 4 to 5 kiloampere-hours had passed through, the acid proved to be free from the above-mentioned contaminations and met all requirements demanded of a pharmaceutically pure acid.

Further experiments have shown that electrolytic purification of the acid may be effected more rapidly and with better output of energy, when working at elevated temperatures of the electrolytic bath, viz. at about 50° C. or more. The heating may be effected either by the electrolyzing electric current itself, or by external means. However, the former method is preferred in most cases, as it may be carried out in a very simple manner.

We have further observed that in some cases, when either none, or only an extremely small quantity of heavy metals are present in the raw acid, the electrolytic separation of

arsenic is not easily attained, but may be promoted by the presence of relatively small quantities of copper salt, probably owing to the fact that a copper arsenide compound is deposited upon the cathode. Therefore small quantities of a copper salt, preferably copper phosphate, are added to the raw acid, to facilitate the separation of the arsenic in absence of heavy metals. The raw acid to be refined is analyzed and the copper salt added to such an extent that the ratio of Cu to As is brought to 1 to at least 2, preferably 1 to 2.5-4.

Example 2

18 A raw acid showing a specific gravity of 1.70 at 17.5° C., corresponding to a concentration of 84.5% H_3PO_4 was subjected to our improved process. This raw acid contained 20 the following contaminations:

	Milligrams per liter
Phosphorous acid	520
Arsenic	115
Heavy metals, except iron	—
Iron	20

25 The raw acid was electrolyzed with platinum anodes and copper cathodes at a bath temperature of about 50° C. with the addition of 0.2 grams of copper phosphate $Cu_3(PO_4)_2 \cdot 3H_2O$, per liter, the cathodic current density being kept at 0.004 amp/cm² and the anodic current density at 0.25 amp/cm². After 3 kiloampere-hours had been passed 30 through, the acid was found to be free from contaminations and answered the requirements of the Pharmacopoeia Germanica, 6th edition. The elevation of the temperature up to 50° C. was attained by simply embalming the electrolyzers. The voltage was thereby reduced from 22.5 to 18 volts, corresponding to a saving of energy of about 20%.

35 The technical progress of our improved process is due to its extraordinary simplicity as compared with the methods hitherto used, as acids of any concentration can be subjected to the refinement according to the present invention and the refined products are immediately ready for further use. This progress 40 was rendered possible by recognizing that for the electrolytic refinement of phosphoric acid it does not suffice to subject the phosphoric acid to the action of a direct current between and acid-proof electrodes, but that the maximum current density of about 1 ampere per 45 square decimeter must be employed in order to avoid the reduction of phosphoric acid, whereas the anodic current density may be higher.

50 We claim:

1. The process of producing chemically pure phosphoric acid from a technical raw acid which comprises subjecting the raw phosphoric acid to electrolysis, cathodes being used upon which the contaminations are

deposited in the form of metals and metalloids without the phosphoric acid being reduced to lower stages of oxidation, the cathodic current density not exceeding 1 ampere per square decimeter.

2. The process of producing chemically pure phosphoric acid from a technical raw acid which comprises subjecting the raw phosphoric acid to electrolysis at a bath temperature exceeding 50° C., cathodes being used upon which the contaminations are deposited in the form of metals and metalloids without the phosphoric acid being reduced to lower stages of oxidation, the cathodic current density not exceeding 1 ampere per square decimeter.

3. The process of producing chemically pure phosphoric acid from a technical raw acid poor in heavy metals which comprises adding a small quantity of a copper salt to the raw phosphoric acid and subjecting the raw acid to electrolysis, cathodes being used upon which contaminations are deposited in the form of metals and metalloids without the phosphoric acid being reduced to lower stages of oxidation, the cathodes current density not exceeding 1 ampere per square decimeter.

4. The process of producing chemically pure phosphoric acid from a technical raw acid poor in heavy metals which comprises adding a small quantity of copper phosphate to the raw phosphoric acid and subjecting the raw acid to electrolysis, cathodes being used upon which the contaminations are deposited in the form of metals and metalloids without the phosphoric acid being reduced to lower stages of oxidation, the cathodic current density not exceeding 1 ampere per square decimeter.

5. The process of producing chemically pure phosphoric acid from a technical raw acid poor in heavy metals which comprises adding a copper salt to the raw phosphoric acid to such an extent that the ratio of Cu to As is confined between the limits 1:2 and 1:4, and subjecting the raw acid to electrolysis, cathodes being used upon which the contaminations are deposited in the form of metals and metalloids without the phosphoric acid being reduced to lower stages of oxidation, the cathodic current density not exceeding 1 ampere per square decimeter.

In testimony whereof, we affix our signatures.

WILHELM MÜLLER.
JOSEF MARTIN MICHEL.
